ICE CUBE VENDING MACHINE

Marion H. Winsett, 1500 Woodhead, Apt. 3,
Houston, Tex. 77019

Original design application Jan. 23, 1970, Ser. No. 21,060,
now Patent No. 222,704. Divided and this application
Dec. 7, 1971, Ser. No. 205,781

Term of patent 14 years

Int. Cl. D20—01

U.S. Cl. D52—3 R

FIG. 1

FIG. 2

FIG. 3

FIG. 4

FIG. 1 is a front, top, and right side isometric view of an ice cube vending machine showing my new design;

FIG. 2 is a rear, bottom, and left side isometric view thereof;

FIG. 3 is a front, top, and right side isometric view of another embodiment of my new design;

FIG. 4 is a rear, bottom, and left side isometric view thereof on a reduced scale.

This application is a division of S.N. D21,060 filed Jan. 23, 1970, now Design Pat. D. 222,704.

I claim:

The ornamental design for an ice cube vending machine, as shown and described.
